MAGNETIC STAND WITH ADJUSTABLE SHUNT

Raymond B. Roof, Battle Creek, Mich.

Application November 21, 1947; Serial No. 787,303

5 Claims. (Cl. 175—367)

1

This invention relates to magnetic holding mechanisms and more particularly to improved structural features thereof.

Broadly the invention comprehends the provision of a holding device of the permanent magnet variety, wherein a shunt gap is provided in a magnetic flux path of the device.

Although numerous permanent magnet holding devices are available, they are either comparatively large in size or do not possess ample magnetic attractive force as to be effectively applicable for many requirements of use. The presently devised magnetic holder through an effective arrangement of permanent magnet, pole pieces, and magnetic shunt members, providing a shunt gap therebetween has made possible the provision of comparatively smaller magnetic holders than heretofore available, having proportionately greater magnetic attraction force. This makes possible the application of this principle to magnetic stands that can be utilized in places previously inaccessible to larger stands.

An object of the invention is the provision of small magnetic holding devices having high magnetic attraction qualities.

Another object of the invention is the provision of permanent magnetic holding devices having increased magnetic attraction force as compared to previously devised permanent magnetic holding devices.

Another object of the invention is the provision of a permanent magnetic holding device having a shunt gap in a flux path thereof providing great holding strength in the major flux path thereof.

A further object of the invention is the provision of a magnetic holding device applicable for holding dial indicators for use with machine tools with a sufficient holding force for accurate dial indicating readings in connection with the tools operation.

A further object of the invention is the provision of a permanent magnet holding device having a shunt circuit in a magnetic flux path thereof and mechanism in the shunt circuit for controlling the magnetic flux in the magnetic flux holding circuit.

Other objects and advantages of the invention will appear from the following description taken in connection with the drawings, forming a part of the specification; and in which:

Fig. 1 is a vertical side plan view of a magnetic stand, embodying the instant invention;

Fig. 2 is a vertical cross-sectional view taken substantially along line 2—2 of Fig. 1;

2

Fig. 3 is a vertical cross-sectional view taken substantially along line 3—3 of Fig. 2;

Fig. 4 is a horizontal cross-sectional view taken substantially along line 4—4 of Fig. 2;

Fig. 5 is a perspective view of the magnetic holding device of the magnetic stand of Fig. 1;

Fig. 6 is a vertical cross-sectional view of a modified form of magnetic holding device;

Fig. 7 is a fragmentary vertical cross-sectional view taken substantially along line 7—7 of Fig. 6; and

Fig. 8 is a fragmentary side plan view of a modified form of the shunt circuit control means shown by Figs. 6 and 7.

15 The present invention is directed at the provision of magnetic holding devices having great strength holding or magnetic attraction qualities so as to be primarily adaptable to stands for supporting dial indicators and the like for use with machine tools. Through the attainment of high magnetic holding force, it is possible to make magnetic holding devices of a size for use in places on machine tools and the like with ample holding force where larger holding devices would be inaccessible.

20 This greater magnetic holding strength is attained through the arrangement of permanent magnet and pole pieces in such a manner and providing a shunt circuit having a shunt gap therein effective to increase the magnetic holding qualities of the major flux circuit produced when the holding device is placed in magnetic holding position.

Under conditions where it is desired to effect 25 an easy removal of the magnetic holding device from a holding position a shunt circuit controlling mechanism is provided which can be easily manipulated to provide a complete shunting of the magnetic holding qualities of the device 30 wherein only residual strength remains and the device can be readily removed from its holding position. When it is again desired to effect a maximum strength holding operation of the device, the control mechanism is manipulated to 35 a position presenting an air gap or shunt gap in the shunt circuit and thereby restoring the maximum magnetic holding quality of the major magnetic flux circuit.

40 Referring to the drawings for more specific details of the invention wherein like numerals refer to like parts and especially with regards to Figs. 1 through 5, 10 represents generally a magnetic stand comprising a magnetic holding device or mechanism 12, a support stem 14 and a dial indicator 16 appropriately clamped to the stem 14.

45 50 55

This stand is adaptable to use in connection with machine tools and the like wherein the mechanism 12 is by magnetic attraction held to a portion of a machine tool and the indicator is moved as desired into engagement with work to be operated upon by the machine.

The mechanism 12 which constitutes the basis of this invention comprises a permanent magnet 18 suitably clamped between a pair of pole pieces or plates 20 and 22 respectively of high magnetic permeability qualities by a bolt 24 of non-magnetic material extending through the pole pieces 20 and 22 and magnet 18, and a pair of plates 26 and 28 respectively arranged in perpendicular relation to the magnet and pole pieces and arranged on ends 30 and 32 respectively of pole pieces 20 and 22.

The plates 26 and 28 of high magnetic permeability material are so arranged relative to the pole pieces and magnet as to extend toward one another and provide an air gap A therebetween, said air gap defining a narrow rectangular passage or opening extending the length of the plates therebetween. The plates 26 and 28 are held in place upon the pole pieces by a block 34 of non-magnetic material suitably secured to the pole pieces by screws 36 of non-magnetic material extending through the block and plates into the pole pieces 20 and 22.

The block 34 is provided with a threaded hole 38 therein for the receipt of the screw threaded end of support stem 14 for securely holding the stem relative to the mechanism 12.

The extremities of the pole pieces 20 and 22 oppositely disposed from the ends 30 and 32 provide the principal holding or magnetic attraction ends of mechanism 12 and are arranged in parallel relation to block 34 and plates 26 and 28. The two vertical exposed sides of pole pieces 20 and 22 also serve as holding surfaces if it is not convenient to use the extremities of 20 and 22 in certain applications.

As a means of inhibiting magnetic particles from clinging to the permanent magnet 18 or to the plates 26 and 28 in the air gap therebetween, a U-shaped shield 40 of non-magnetic material is slipped into appropriate grooves in the pole pieces, plates, and block so as to extend along three sides of the permanent magnet and provide in connection with the block to which it is suitably secured a complete enclosing of the magnet.

As can be seen from Fig. 3, the shield coincides with the holding faces of the pole pieces in flush relation thereto and as such does not interfere with the holding qualities thereof.

The air gap A provided between the plates 26 and 28 together with the plates constitutes a shunt circuit for the magnetic holding mechanism and forms a part of the minor flux path designated by the dotted lines B of Fig. 3 and as such provides a holding magnet of great strength whereby through the predetermination of size of the air gap the magnetic flux in the holding circuit is raised to a maximum. This holding circuit is designated by the dotted lines C of Fig. 3 wherein the holding ends of the mechanism 12 are in contact with the surface of some magnetic material, such as, a part of a machine tool which forms a part of the flux path.

Figs. 6 and 7 are directed to the provision of a magnetic holding mechanism embodying the general principle of the structures of Fig. 1 through 5 and incorporating shunt circuit control means wherein instead of the plates 26 and 28 provided by the structure of Fig. 3 plates 42 and 44 of a

more substantial thickness than plates 26 and 28 are provided having a passage 46 extending therebetween and having rotatable therein in close bearing relation a shaft 48 composed of a laminated structure of a strip of non-magnetic material 50 such as brass or the like sandwiched between a pair of substantially semi-circular cross-section members 52 of high permeability material such as mild steel or similar metal. The inwardly extending ends of the plates 42 and 44 are provided with semi-circular concave portions 54 and 56 respectively within which the semi-circular exterior surfaces of the shaft are arranged to be in good physical contact. The shaft 48 is provided with a suitable manually actuatable knob 58 for the proper setting of the shaft relative to the plates 42 and 44 for an "on" or "off" operation of the mechanism.

The non-magnetic material 50 is of a predetermined thickness so as to provide a suitable leakage or shunt gap such that upon the movement of the shaft to a position wherein the brass strip is in dotted line position of Fig. 7 the magnetic holding position of the mechanism is at its maximum holding force. With the shaft 48 in full line position of Fig. 7 the members 52 because of their close physical contacting relation with the plates 42 and 44 a complete shunting of the magnet is effected thus detracting from the holding qualities of the magnetic holding portion of the mechanism and reducing the magnetic strength to a low residual value.

With the provision of the control shaft 48, the mechanism can be readily removed from magnetic holding position merely by a complete shunting of the magnetic flux lines through the manipulation of shaft 48 through 90°.

Fig. 8 illustrates a modified form of the control shaft of Figs. 6 and 7 wherein a cylindrical shaft 60 of high magnetic permeability material such as mild steel or the like is provided having a pair of arcuate inserts 62 made of non-magnetic material such as brass arranged in the exterior of the shaft oppositely disposed from one another. The inserts 62 in providing leakage or shunt gaps are equally effective as strip 50 of the structure shown by Fig. 7.

Although the shunt circuit gap and control mechanism are shown by the drawings in a specific arrangement relative to the pole pieces and permanent magnet they can be placed anywhere on the pole pieces 20 and 22 and will function equally as well as the structures shown and described hereinabove.

While this invention has been described in connection with certain specific embodiments, the principle involved is susceptible of numerous other applications that will readily occur to persons skilled in the art. The invention, therefore, is limited only as indicated by the scope of the appended claims.

What I claim is:

1. A holding device comprising a permanent magnet, a pair of pole pieces disposed on opposite sides of the magnet terminating at one end in work engaging surfaces spaced apart the thickness of the magnet and at their other ends being disposed toward one another but spaced apart a predetermined distance and a magnetic permeable member closely embraced and rotatable between the ends of the pole pieces disposed toward one another having a flat section of non-permeable material passing through the axis of rotation of the magnetic member incorporated therein in such that in one position of the magnetic per-

meable member the work engaging surfaces of the pole pieces will have maximum holding strength and upon rotation of the member 90°, the work engaging surfaces will have minimum holding strength.

2. A holding device comprising a permanent magnet, a pair of relatively flat magnetically permeable members arranged in parallel array on opposite sides of the magnet and a member disposed outwardly of the magnet and rotatably secured between opposed ends of the magnetically permeable members, said member being of magnetic permeability and having a non-magnetic flat element of uniform thickness incorporating centrally therein adapted to provide a leakage gap across the opposed ends of the magnetically permeable members for one position of the rotatable member with the flat element lying parallel to the magnetically permeable members but which are displaced from leakage gap position upon rotation of the rotatable member 90° from the aforesaid position thereby providing a flux bridging path across the rotatable member between the opposed ends of the magnetically permeable members.

3. A holding device comprising a permanent magnet, a pair of pole pieces arranged on opposite sides of the magnet each having work engaging surfaces on one end and having their opposite ends in opposed spaced relation, said opposed spaced ends having like concave surfaces, and a cylindrical member fitted between the opposed concave surfaces in close bearing and rotative relation, said cylindrical member comprising a portion of magnetically permeable material and a flat portion of non-magnetic material arranged centrally of the magnetically permeable portion separating the magnetically permeable portion into two like spaced arcuate sections such that in one position of the cylindrical member a leakage gap is provided for maximum holding quality at the work engaging surfaces of the pole pieces and in a second position of the cylindrical member upon rotation of 90° from the first position, the holding quality at the work engaging surfaces of the pole pieces is at a minimum.

4. A holding device comprising a permanent magnet, a pair of pole pieces arranged on opposite sides of the magnet each having work engaging surfaces on one end and having their opposite ends in opposed spaced relation, said opposed

- spaced ends having like concave surfaces, and a cylindrical member fitted between the opposed concave surfaces in close bearing and rotative relation, said cylindrical member comprising a pair of like arcuate portions of magnetically permeable material spaced apart and separated by a flat portion of non-magnetic material such that in one position of the cylindrical member a leakage gap is provided for maximum holding quality at the work engaging surfaces of the pole pieces and in a second position of the cylindrical member upon rotation of 90° from the first position, the holding quality at the work engaging surfaces of the pole pieces is at a minimum.
5. A holding device comprising a permanent magnet, a pair of like pole pieces of high magnetic permeability secured to the permanent magnet on opposite sides thereof extending parallel to one another terminating in work engaging surfaces on one end, a pair of like high magnetic permeability members, one secured upon each of the respective pole pieces on the ends thereof oppositely disposed from the work engaging faces thereof, said members extending in a direction toward one another and spaced apart a predetermined distance providing opposed arcuate surfaces, and a cylindrical member mounted for rotation in the space between the arcuate surfaces comprising a pair of semi-cylindrical members of high magnetic permeability having a flat section member of uniform thickness non-magnetic permeability material sandwiched therebetween.
